UNITED STATES PATENT OFFICE.

JOHN C. WARNER, OF SCHENECTADY, NEW YORK, ASSIGNOR TO GENERAL ELECTRIC COMPANY, A CORPORATION OF NEW YORK.

ELECTRON-DISCHARGE APPARATUS.

Application filed March 5, 1925. Serial No. 13,042.

To all whom it may concern:

Be it known that I, JOHN C. WARNER, a citizen of the United States, residing in Schenectady, in the county of Schenectady, State of New York, have invented certain new and useful Improvements in Electron-Discharge Apparatus, of which the following is a specification.

My present invention relates to electron discharge apparatus, and more particularly to the operation of devices of the thermionic type having at least four electrodes.

One of the objects of my invention is to provide improved circuit organizations whereby devices of the type mentioned may be more particularly adapted for the production of oscillations.

In connection with electron discharge devices of the thermionic type having a grid for controlling the flow of current between cathode and anode, it has been proposed to employ a second grid between the cathode and the control grid and to impress upon this second grid a constant positive potential somewhat lower than that of the anode.

A grid used in this way is commonly known as a space charge grid. The purpose of this grid is to lower the impedance between the cathode and anode, and for this purpose the grid has ordinarily been maintained at a constant positive potential.

When such a device is used for the purpose of producing oscillations or for other purposes where the anode current may at times fall to a low value, it is not necessary to maintain the positive potential on the space charge grid at all times, it being sufficient for all practical purposes merely to have the desired positive potential on the grid at times when the current flowing to the anode is comparatively large. When the space charge grid is positive all the time it is drawing current and consuming energy.

A more specific object of my invention is to provide a means for automatically varying the potential of the space charge grid in such a way that it will be of such a positive value as to appreciably lower the impedance of the device only when the current flowing through the anode is appreciably above its minimum value. At other times the space charge grid may be maintained at zero potential with respect to the cathode or even at a negative potential without inter-

fering with the satisfactory operation of the device, and by this expedient the losses in the system may be reduced and the efficiency thereby increased.

Still another object of my invention is to provide a means for efficiently interrupting the production of oscillations by a device of the type mentioned for the purpose of signalling.

The novel features which I believe to be characteristic of my invention are set forth with particularity in the appended claims. My invention itself, however, both as to its organization and method of operation, will best be understood by reference to the following description taken in connection with the accompanying drawing, in which Figs. 1, 2, and 3 illustrate diagrammatically three different circuit organizations whereby my invention may be carried into effect.

I have indicated in the drawing by conventional symbols an electron discharge device 1, having the usual electron emitting cathode 2, anode 3, a discharge control grid 4 and a space grid 5. In the system shown in Fig. 1 an oscillating circuit comprising inductances 6 and 7, and capacities 8 and 9, is connected between the anode and the discharge control grid. The inductance 6 of the oscillating circuit is variably coupled to a load circuit 10 and to a coil 11, which is included in the circuit between the cathode and the space charge grid 5. By this means a voltage is impressed upon the space charge grid, which is in phase with the voltage of the control grid. In this way the space charge grid is made positive at the time when the maximum plate current is flowing. The plate impedance is thus reduced by a reduction of the space charge between cathode and anode. During that part of the cycle when the plate current is low, the space charge grid is negative and thus does not absorb any power.

In Fig. 2 a similar arrangement is shown, but in this case the main oscillating circuit, made up of inductance 12 and capacity 13, is coupled by the variable couplings 14, 15 and 16 to the plate circuit and to both of the grid circuits.

The mean potential of either grid may be varied by suitable battery bias or grid leak bias, as may be required to secure the most efficient operation of the particular tube employed.

The space charge grid, when employed in the manner indicated, also has other advantages in addition to the neutralization of space charge. In a power tube which has 5 a low plate impedance, the plate current sometimes rises to a dangerously high value when the tube for any reason stops oscillating. In the system described, the voltage of the space grid is dependent entirely on 10 the current in the oscillating circuit and when this current stops for any reason the plate impedance automatically increases to a high value, thus protecting the output from damage from overload.

15 The use of the space charge grid in this way also furnishes a convenient instrumentality for starting and stopping oscillations for signalling purposes. This may be accomplished by means of a key associated 20 with the circuit of the space charge grid. In Fig. 1 I have shown the key 17 so arranged that it opens the circuit of the space charge grid. This will raise the impedance of the output to such a value that oscillations will be interrupted. In the arrangement shown in Fig. 2 the key 17 is so located 25 that it short circuits the inductance in the circuit of the space charge grid, and thereby causes a high increase in the impedance of 30 the output and interrupts the production of oscillations.

While it will usually be preferable to employ the grid nearest the cathode as the space charge grid, devices of the type here 35 under consideration may be operated in much the same manner with the grid nearest the anode employed as an auxiliary grid and the grid nearest the cathode as control grid. The arrangement in Fig. 3 shows the 40 connections made in this manner, the circuit otherwise being arranged in the same way as the circuit shown in Fig. 1.

While I have shown and described the preferred embodiments of my invention, it 45 will be apparent that many modifications in the circuit arrangement can be made without departing from the scope of my invention as set forth in the appended claims.

What I claim as new and desire to secure 50 by Letters Patent of the United States is:—

1. The combination with an electron discharge device having an electron emitting cathode, an anode and two grids interposed between cathode and anode, one of said 55 grids being nearer the anode than the other, of means for producing oscillations comprising an oscillating circuit connected to the anode and one of the grids and a coupling between the oscillating circuit and a 60 circuit of the other grid.

2. The combination with an electron dis-

charge device having an electron emitting cathode, an anode and two grids interposed between cathode and anode, one of said grids being nearer the anode than the other, 65 of means for producing oscillations comprising an oscillating circuit connected to the anode and one of the grids and a coupling between the oscillating circuit and a circuit of the other grid, and means associated 70 with the circuit of the other grid for interrupting the production of oscillations.

3. The combination with an electron discharge device having an electron emitting cathode, an anode and two grids interposed 75 between cathode and anode, one of said grids being nearer the anode than the other, of means for producing oscillations comprising an oscillating circuit associated with the anode and one of the grids and a coupling between the oscillating circuit and a circuit of the other grid.

4. The combination with an electron discharge device having an electron emitting cathode, an anode and two grids interposed 85 between cathode and anode, one of said grids being nearer the anode than the other, of means for producing oscillations comprising an oscillating circuit associated with the anode and one of the grids and a coupling 90 between the oscillating circuit and a circuit of the other grid, and means associated with the circuit of the other grid for interrupting the production of oscillations.

5. The combination with an electron discharge device having an electron emitting cathode, an anode and two grids interposed 95 between cathode and anode, one of said grids being nearer the anode than the other, of means for producing oscillations, comprising an oscillating circuit connected to the anode and the grid nearest the anode and a coupling between the oscillating circuit and a circuit of the grid nearest the cathode.

6. The combination with an electron discharge device having an electron emitting cathode, an anode and two grids interposed between cathode and anode, one of said grids being nearer the anode than the other, 110 of means for producing oscillations, comprising an oscillating circuit connected to the anode and the grid nearest the anode, a coupling between the oscillating circuit and a circuit of the grid nearest the cathode, 115 and means associated with the circuit of the grid nearest the cathode for interrupting the production of oscillations.

In witness whereof, I have hereunto set my hand this 3rd day of March, 1925.

JOHN C. WARNER.
